HOPPER TYPE SCREEN UNIT FOR CLASSIFYING AND SEPARATING LIQUIDS AND SOLIDS

Marvin E. Ginaven, Springfield, Ohio, assignor to The
Bauer Bros. Co., Springfield, Ohio

Filed Sept. 15, 1971, Ser. No. 180,935

Term of patent 14 years

Int. Cl. D15—99

U.S. Cl. D55—1 R

FIG-1

FIG-4

FIG-3

FIG-2

FIG. 1 is a perspective view of a hopper type screen unit for classifying and separating liquids and solids showing my new design;

FIG. 2 is a top plan view of a hopper type screen unit for classifying and separating liquids and solids shown in FIG. 1;

FIG. 3 is a side elevation view of a hopper type screen unit for classifying and separating liquids and solids of FIG. 1; and

FIG. 4 is an enlarged segment of the screen taken on line 4—4 of FIG. 1.

I claim:

The ornamental design for a hopper type screen unit for classifying and separating liquids and solids, substantially as shown and described.
